CLEANSING SWAB

Minna I. Reach, Pasadena, Calif.

Application September 30, 1935, Serial No. 42,806

7 Claims. (Cl. 15—209)

This invention relates to an improvement in toilet bowl cleaners.

The general object of this invention is to provide an improved toilet bowl cleaner including an operating handle.

A more specific object of the invention is to provide a novel toilet bowl cleaner including a swab made of shredded tissue paper which disintegrates in the water after it has served its purpose.

10 A further object of the invention is to provide an improved toilet bowl cleaner including a swab which contains a disinfectant.

Other objects and the advantages of the invention will be apparent from the following description taken in connection with the accompanying drawing, wherein:

Fig. 1 is a side elevation showing my improved toilet bowl cleaner and the operating handle;

Fig. 2 is an extended view showing the component parts of my improved toilet bowl cleaner swab in perspective and in relative position of assembly;

Fig. 3 is a plan view of the swab preparatory to being rolled into a cylinder;

25 Fig. 4 is a view similar to Fig. 3 showing the swab partly rolled;

Fig. 5 is an end view of the swab;

Fig. 6 is a side elevation partly in section showing my improved holder;

30 Fig. 7 is a detail showing one of the fingers of my improved holder;

Fig. 8 is a plan or bottom view of a modified form of my invention, and

Fig. 9 is a transverse sectional view on line 35 9—9, Fig. 8.

This application is a continuation in part of my copending application, Serial No. 721,107, filed April 18, 1934.

40 Referring to the drawing by reference characters I have indicated my improved toilet bowl cleaner generally at 10. As shown the cleaner includes a swab member 12 and a holder member 13.

45 The swab member 12 is made of a plurality of layers of paper rolled in a substantially cylindrical form. The paper preferably is of such a nature that it will quickly disintegrate when moist. In constructing the swab I take one or more layers of tissue indicated at 14 (and shown as two in number), slit the edges of these sheets as at 14' and lay one upon the other.

50 A second group of elongated thin paper strips 15 (shown as four in number) is provided with slits 15' and arranged with the ends of strips 15 overlapping the strips 14, as shown in Figs. 2 and

3. The strips 15 are narrower than the strips 14 and upon one end of the upper strip 15 I arrange a center or core member 16. This core member comprises shredded tissue paper which is lightly compressed to form a more or less compact mass. 5

Adjacent the core member I arrange a coating 17 of adhesive which may be made of the following ingredients:

	Pounds
Glucose	80
Water	15
Glycerine	5
Powdered gum acacia	1/2

This adhesive will penetrate and secure the 15 several layers of paper together and readily dis-solves when immersed in, or moistened with, water.

An envelope preferably made of tissue paper is secured to the top strip of paper 15 with the adhesive 17 and contains a suitable disinfectant, 20 such as trisodium phosphate.

After the parts are assembled as shown in Fig. 3 the layers 15 are rolled so that the adhesive 17 engages the core 16 and the rolling is con-tinued as shown in Fig. 4 and is then further 25 continued until the cylinder is complete and the free end is held in position by a glued area 18.

The slits in the end of the sheets 14 and 15 produce a plurality of tongues which give added 30 flexibility and produce a cleansing and scrubbing action.

The holder 13 consists of a pair of arms 28 formed of a single piece of spring wire, the in-termediate portions of which are bent to form 35 a closed loop 21. On the ends of each arm 28 I secure a finger member 22 which may be made of metal or rubber and which as shown includes inwardly concave portions 23 which are knurled as at 24.

40 When it is desired to use my improved toilet bowl cleaner, a swab 12 is engaged between the fingers 22 of the holder 13. As the bowl is cleaned water penetrates the paper and softens the ad-hesive at 17 and 18, and dissolves the disinfectant 45 in the envelope 19 and causes the entire swab to begin to disintegrate.

When the cleaning is complete the holder is re-leased leaving the swab 12 in the bowl. As the adhesive softens, the swab further disintegrates 50 and may be flushed from the bowl.

The swab may be used without the holder 13 and it may be used for general cleansing pur-poses.

In the modified form shown in Figs. 8 and 9 I 55

have shown a paper sponge B formed of a plurality of shredded strips 1 of a disintegratable paper and which has its central portion 2 treated with a water soluble binder or adhesive.

5 The water soluble binder or adhesive I prefer to use with my invention is a weakened solution such as a twenty per cent (20%) solution of acacia or gum arabic, but it is understood that any other suitable water soluble binder or adhesive may be used, such as silicate of soda, the various vegetable gums, gum karaya, tragacanth, dextrin or British gum; adhesives made from glues, starches and cereals; adhesives of either vegetable or animal matters, or such adhesives 10 made from materials that act as an adhesive and are readily soluble in water, gelatines, albumin, agar, and sugar derivatives may be suitable; as well as chemical salts which act as an adhesive and are easily fusible and water soluble. The 15 only requirement of the chemical used is that it be of such character and strength as to act to bind the shredded paper in a wadded mass and retard the disintegration of such shredded paper for a short space of time until the washing operation 20 has been completed and which chemical in the strength used will also be readily soluble in water and will not leave a scum or oil on the article being washed or on the water with which it is used.

25 30 In carrying out the invention as disclosed in Figs. 8 and 9 a mass of shredded paper strips 1 may be of sufficient quantity to make a sponge of the desired size and shape which may be placed upon a supporting surface and a predetermined quantity of a water soluble binder or adhesive 35 may be dropped upon a central portion of such mass of shredded paper after which the edges of the mass of shredded paper are folded over each other so as to enclose such water soluble binder 40 or adhesive applied thereto and the same is then compressed so that the central portion thereof is wadded into the desired shape, but the exterior surfaces thereof are covered with protruding free strips of shredded paper which thereby enhance 45 the appearance of the article, as well as presenting a sponge upon its contact with water with a substantially immediately disintegratable portion of paper strips which may aid in the washing operation.

50 55 I have also discovered that the finished article may be made more pliable or flexible for immediate use as a sponge for washing articles with water that may be accomplished by adding approximately one part of vegetable oil, such as castor oil, to eight parts of the water soluble binder and adhesive hereinbefore referred to, such as the twenty per cent solution of gum arabic 60 thereby forming an emulsion into which the shredded paper is immersed, or associated with, in either manner hereinabove referred to.

From the foregoing description it will be apparent that I have invented a novel toilet bowl cleaner which can be economically manufactured and which is highly efficient in use.

Having thus described my invention I claim:

1. In a cleaning swab, an inner wrapping of superimposed, water permeable sheets of paper and a second wrapping of superimposed water permeable sheets of paper of greater width than said first mentioned sheets of paper and disposed around said first wrapping, and a coating of water soluble adhesive penetrating said second sheets and securing them in position about said first mentioned sheets. 5

2. In a cleaning swab, a core of compressed water permeable shredded paper, a wrapping of superimposed, slitted edged, water permeable, sheets of paper secured to said core by a water soluble adhesive, said adhesive coating extending through said superimposed sheets, a second wrapping of superimposed, slitted edged, water permeable, sheets of paper of greater width than said first mentioned sheets of paper and disposed around said first wrapping, and a coating of water soluble adhesive penetrating said second sheets and securing them in position about said first mentioned sheets. 10 15

3. In a cleaning swab, a core of compressed water permeable shredded paper, an envelope formed of water permeable paper and arranged adjacent to said core, a water soluble disinfectant in said envelope, a wrapping of superimposed, slitted edged, water permeable, sheets of paper secured to said core by a water soluble adhesive, said adhesive coating extending through all of said superimposed sheets, a second wrapping of superimposed, slitted edged water permeable sheets of paper of greater width than said first mentioned sheets of paper and disposed around said first wrapping, and a coating of water soluble adhesive penetrating all of said second sheets and securing them in position about said first mentioned sheets. 20 25 30

4. An article of manufacture comprising a plurality of strands of water soluble material the interior of which has commingled therewith adhesive and binder more slowly soluble than the said material and the exterior of which has protruding therefrom substantially free strands of the said material. 40 45

5. An article of manufacture comprising a quantity of water soluble material the body portion of which has commingled therewith an emulsion of approximately one part of a vegetable oil and approximately eight parts of adhesive and binder more slowly soluble than said material. 50

6. An article of manufacture comprising a swab the main body portion of which consists of a wadded mass of absorbent material readily soluble in water and coated with an adhesive which is more slowly soluble than said absorbent material, which adhesive serves to hold the material in wadded form and retard the disintegration thereof. 55

7. A cleaning swab comprising a wadded, shredded paper core having a binder which is more slowly soluble than the paper, and a plurality of strips of paper arranged about the core and protruding therefrom. 60
